UNITED STATES PATENT OFFICE.

ALONZO G. CARMAN, OF MARENGO, ILLINOIS.

ATTACHMENT FOR WINDMILLS.

SPECIFICATION forming part of Letters Patent No. 275,140, dated April 3, 1883.

Application filed February 5, 1883. (No model.)

To all whom it may concern:

Be it known that I, ALONZO G. CARMAN, a citizen of the United States of America, residing at Marengo, in the county of McHenry 5 and State of Illinois, have invented certain new and useful Improvements in Attachments for Windmills; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to a means for preventing a wind-wheel from being thrown out of the wind by the reaction of the gearing which intermediately connects the wheel with devices mounted on the tower for transmitting motion.

20 In the accompanying drawings, Figure 1 is a side elevation of a sufficient portion of a windmill for illustration of my invention. Fig. 2 is a view in elevation of the same parts, looking toward the end of the vane.

25 The letter A designates the tower centrally, upon the top of which is secured a horizontal disk, B, having ratchet-teeth formed upon the margin of its under side.

30 C is the turn-table, from which a suitable pivot-pin extends downward through the center of the disk B and tower A. The turn-table may be mounted to revolve upon the disk B in any other suitable manner. To the rear end of the turn-table is secured the vane D, 35 the arm d of which is provided with a tenon, e, (shown in dotted lines,) which fits in a socket in the end of the turn-table, and is secured therein by a pin, e'. On the lower edge of the vane D is formed a shoulder, e, in which is 40 formed a bearing for a rock-shaft, F, which has its other bearing in the rear end of the turn-table. Upon this rock-shaft is firmly secured a detent-pawl, G, having its lower end curved under the margin of the disk B, and 45 provided with a catch, g, to engage the ratchet-teeth of said disk. The opposite end of this pawl projects beyond the shaft F, and is weighted, as shown at h, in order to keep the 50 detaining-catch of the pawl up against the margin of the disk. Upon the shaft F is also

rigidly secured a trip-vane, I, which normally projects directly downward.

Referring now to Fig. 2, we will suppose the wind-wheel, which is not shown, to be in position to catch the wind, and that the reaction of the gearing tends to move the turn-table in the direction indicated by the arrow No. 1. This would gradually carry the wheel away from the wind, and is a very serious defect in many windmills. By my improvement this effect of 60 reaction is prevented, as it will be observed that the engagement of the pawl G with the ratchet-teeth of the disk B will effectually prevent such effects. If, however, the wind should change in such manner as to render the movement of the turn-table in the direction of arrow No. 1 necessary, the trip-vane I will be blown to one side, as shown in dotted lines, Fig. 2, and turn the rock-shaft F so that it will carry the pawl G downward, as also shown 65 in dotted lines, and out of engagement with the ratchet-teeth of disk B. The setting-vane D can then shift with the wind and operate the turn-table to bring the wheel in the wind's eye, and at such time the trip-vane I will resume its vertical position and bring the pawl G again into engagement with the ratchet-teeth of the disk. If, by the change of the 70 wind, it becomes necessary that the turn-table move in a direction opposite to that indicated by arrow No. 1, it is obvious that when the wind strikes the vane D in the direction indicated by arrow No. 2 its pressure will cause the inclined catch g of the pawl to slip under the inclines of the ratchet-teeth and permit 75 the proper movement of the turn-table. By detachably connecting the arm of vane D with the turn-table, as shown, I secure great convenience in mounting the shaft F in its bearings, being thus enabled to form these bearings directly in the edge of shoulder e and the rear end of the turn-table, instead of providing 80 separately-attached bearing-boxes.

I wish it to be understood that I do not confine myself to the exact construction and arrangement of parts, as shown in the drawings, 85 as it is obvious that they may be greatly varied, while still accomplishing the object of the invention, and without departing from the true spirit and scope thereof.

What I claim is—

1. In a windmill, the turn-table A, having ratchet-disk B, in combination with the vane D, having pivoted shaft F, carrying a weight-ed pawl, G, and trip-vane I, substantially as shown, and for the purpose set forth.

2. The combination, with the turn-table and the pawl-shaft F, having one of its bearings in the rear end of the turn-table, of the detacha-

ble vane D, provided with the shoulder *e*, having formed therein the other bearing for said pawl-shaft, substantially as described.

In testimony whereof I affix my signature in presence of two witnesses.

ALONZO G. CARMAN.
